DESIGN FOR A MINIATURE VISE

Walter G. Bihler, Detroit, Mich., assignor to Special Machine & Engineering Co., Hazel
Park, Mich., a corporation of Michigan

Application January 26, 1946, Serial No. 125,996

Term of patent 14 years

(Cl. D54—14)

To all whom it may concern:

Be it known that I, Walter G. Bihler, a citizen of the United States, residing at Detroit, in the county of Wayne and State of Michigan, have invented a new, original, and ornamental Design for a Miniature Vise, of which the following is a specification, reference being had to the accompanying drawing, forming part thereof.

I claim:

The ornamental design for a miniature vise, substantially as shown.

WALTER G. BIHLER.
